CONTROL MEANS FOR LIGHTER
MECHANISMThomas L. Ferrall, Detroit, Mich., assignor to
Roberts Brass Manufacturing Company, De-
troit, Mich., a corporation of Michigan

Application January 18, 1934, Serial No. 707,183

4 Claims. (Cl. 158—117.1)

The invention relates to lighters for gas stoves and more particularly to constructions providing for the lighting of a plurality of different burners, or groups of burners requiring separate pilot lights. It is the object of the invention to automatically shut off the supply of gas to all of the burners when the flame of one pilot has been extinguished, thereby necessitating the relighting of such pilot before the burners can be operated. It is a further object to effect this control where any one of the several pilots has been extinguished and without the necessity of duplicating all of the mechanisms for each pilot. With these objects in view the invention consists in the construction as hereinafter described.

In the drawings:

Fig. 1 is a perspective view of my improved lighter control means in connection with an oven burner lighter and a top burner lighter;

Fig. 2 is a plan view showing a construction using three lighters;

Fig. 3 is a section on line 3—3 of Fig. 2;

Fig. 4 is a section through the main gas control valve;

Fig. 5 is a section through the pilot control valve showing a slightly modified construction;

Fig. 6 is a side elevation of one of the pilots;

Fig. 7 is a diagram illustrating another modification.

As my lighter control means is applicable to various gas stoves without regard to the specific construction of the same, it is unnecessary to illustrate such construction further than to show some of the burners and the lighters therefor. Thus as shown in Fig. 1, A is the main gas supply conduit for the gas stove, B is one of the top burners of the stove receiving its supply of gas from the conduit A and provided with the usual mixing tube C and controlling valve D. E is the valve controlling the oven burners (not shown) this being also supplied with gas from the conduit A. The burner B is one of a group, the others of which are not shown and all of which are automatically lighted from a single pilot flame. The lighter construction comprises a jet tube F with an air mixing tube G surrounding the same, and a frusto-conical shield H for protecting the pilot flame from drafts. These parts are mounted on a suitable supporting bracket I on the frame of the stove (not shown). Projecting laterally from the shield H are the flame conveying tubes J which extend to each of the burners B and are so constructed as to receive gas therefrom. The arrangement is such that when ever the valve D is open to supply the burner B with gas, a jet of gas

is directed into the tube J producing a combustible mixture therein which extends to the pilot, thereby effecting propagation of the pilot flame to the burner.

For lighting the oven burner I have provided a lighter mechanism comprising a pilot jet K mounted upon a vertical mixing tube L having a laterally extending perforated tube L' which extends into the oven and into lighting proximity with the burner therein. The mixing tube L receives gas from a conduit M which is connected to the valve E for the oven burner, the arrangement being such that whenever said valve is open to supply gas to the burner, gas will also pass through the tube M to the mixing tube L and laterally extending perforated tube L'. The tube L has a jet aperture L² in the top thereof which directs gas towards the pilot K and perforations of the tube L', thereby causing the propagation of flame from the jet inward to the burner. The elements L and K are preferably located between the outer wall and the lining of the oven, so as to protect the pilot flame from drafts and as will be later explained, to conduct away any escaping gas into the chimney flue.

My automatic control mechanism comprises a shut-off valve N located in the main supply conduit A. This valve as shown in Fig. 4 has an apertured seat N' and a cooperating valve disk N², which latter is mounted on a stem N³ passing outward through a packing gland N⁴. A spring N⁵ bearing against the disk N² serves to yieldably hold said disk to its seat. Aligned with the stem N³ is an operating rod O which passes over the pilot light and is slidably supported in a bifurcated bracket I' extending upward from the bracket I. At the outer end of the rod O is an operating knob O' which when pressed will actuate the stem N³ to force the valve disc N² away from its seat. Beneath the rod O is a U-shaped bimetal thermostatic bar P, one end of which is mounted on a post P' rising from a plate P² mounted on the tube G. The bend in this bar is above the pilot light from the jet tube F and under normal conditions when the pilot is lighted, will be heated so that its free end is bent upward adjacent to the rod O. O² is a collar on the rod O adapted to engage the end of the bar P to hold the valve disc N² in open position. Thus as long as the pilot is lighted the valve N² when once opened by operation of the rod O will remain open, thereby supplying gas to the burners of the stove. As soon, however, as the pilot flame is extinguished the bar P will cool and bend down-

ward so as to disengage the collar O² and permit the spring N⁵ to close the valve.

The pilot for the oven burner is provided with a similar control comprising a U-shaped bi-metal 5 thermostatic bar Q arranged above the flame from the jet tube K. Instead, however, of using this control for operating a valve in the main supply conduit, it controls a valve R which supplies gas to the jet tube F. The arrangement is 10 such that the pilot flame from the jet tube K by expanding the bar Q will hold the valve R in open position where gas is supplied to the jet tube F through a conduit R', but if the flame from the jet K is extinguished, this will effect the closing 15 of the valve R which in turn will extinguish the flame from the jet tube F, bringing about the closing of the valve N² as previously described.

The supply of gas to the valve R may if desired be taken from the portion A' of the pipe A 20 which is beyond the valve N and supplies the burners. Such a connection is indicated at S (Fig. 5). Inasmuch, however, as the pilot K is preferably located between the lining and outer wall of the oven, which space is connected with 25 the chimney flue, it is not so important to cut off the supply of gas thereto. In other words, the small discharge of gas from such jet will be rapidly carried away and up the chimney without permitting escape into the room or the forming 30 of an explosive mixture in the oven. Therefore I preferably connect the valve R with the conduit A on the supply side of the valve N, so that at all times gas will be furnished to the nozzle K. As shown, this is accomplished by forming the 35 valve N with a nipple N⁶ to which is connected a pipe R³ leading to the valve R, said nipple being on the gas supply side of the valve N².

For certain uses, as for instance hotel gas ranges, the number of top burners is more than 40 can be lighted from a single pilot. Thus, as shown in Fig. 2, the burners B, B', B² and B³ are all lighted from the pilot F through the flame conducting tubes J, J', J² and J³. In addition to these burners, there are two or more burners, B⁴ 45 and B⁵, which must be lighted from a separate pilot. For such a construction I remove the control rod O from the pilot F and arrange it in connection with a pilot T for lighting the burners B⁴ and B⁵. The valve N is also transferred in position 50 so as to be operated by the rod O, as previously described, but to be directly controlled by the thermostat of the pilot T. The thermostat of the pilot F controls a valve U which is similar in construction to the valve R and which supplies 55 gas to the pilot T through a conduit T'. With this construction, if any one of the pilot lights is extinguished, this will cause the closing of the valve N² which will shut off the supply of gas to all of the burners. If the extinguished pilot is 60 from the jet K, then gas will be cut off from the pilots F and T, but the jet K will still be supplied with gas so that it may be readily ignited. If the pilot F is extinguished, this will cut off the supply of gas to the pilot T, which will cause the 65 closing of the valve N², but gas will still be supplied to the jet of the extinguished pilot. In the same manner, if the pilot T is extinguished, this will cause the closing of the valve N², but will permit the pilots K and F to continue burning and 70 will supply gas to the extinguished pilot T. Thus it will be noted that with this construction as well as with the construction previously described, there is only one extinguished pilot which can be still supplied with gas. Thus the amount of gas 75 which can be discharged is not sufficient to

bring about a dangerous condition, either by way of forming an explosive mixture in the room or a poisoning of the atmosphere.

With the alternative gas supply connection for the pilots indicated in Fig. 5, leakage of gas from any pilot is prevented but to relight the jets it would be necessary to hold the valve N² open by pressure on the knob O' for a sufficient length of time to successively heat up all of the thermostats. There is therefore an advantage in the 10 use of the construction of the connection shown in Fig. 1, as with this there is always a supply of gas to the jet K which can be instantaneously lighted and in case the other pilots have been extinguished they may be successively lighted 15 until the last of the series is reached. The knob O' may then be operated to open the valve N² and supply gas to the burners.

For certain installations it is desirable to provide a plurality of pilots which are supplied with 20 gas at all times and which therefore can be lighted without delay. Such a construction is diagrammatically illustrated in Fig. 7 in which W and W' are two pilots which are constantly supplied with gas from the main gas pipe A 25 through the branch pipes W² and W³. The pilot W controls the thermostatic valve W⁴ and the pilot W' controls the thermostatic valve W⁵, both of which are in a gas supply line W⁶ for a third pilot W⁷. The latter controls the main valve N 30 which is opened by the operating rod O.

With this construction the extinguishing of any one of the pilots will bring about the closing of the main valve N in the same way as in the constructions previously described. Also, the extinguishing of either of the pilots W or W' will cut off the gas supply to the pilot W⁷. There is, however, this difference from the constructions previously described, that the pilots W and W' are constantly supplied with gas so that either one 40 may be instantly lighted if it has been extinguished. This, while rendering it possible to have two extinguished pilots supplied with gas, nevertheless has the advantage of greater ease in relighting than with the constructions previously 45 described, which require successive lighting of the pilots.

What I claim as my invention is:

1. In combination, a burner, a pilot in lighting proximity to said burner, a second burner, a pilot in lighting proximity to said second burner, a gas supply conduit for said burners, a spring pressed valve controlling the flow of gas through said conduit to said burners, a second spring pressed valve, a conduit for conducting gas from the supply side of said supply conduit to the second valve, branch conduits for conducting gas from the second valve to the pilots, the branch conduit to the second pilot being upon the supply side of the second valve, the branch conduit to the first pilot being upon the discharge side of said second valve, a heat responsive element in position to be heated by the second mentioned pilot when lighted, an automatic push rod movable by the heat responsive element when heated by the second mentioned pilot for opening the second mentioned valve, said second mentioned valve being movable by its spring to closed position to cut off the supply of gas to the first mentioned pilot when the second mentioned pilot is extinguished, a manually operable push rod for opening the first mentioned valve, said rod extending over the first mentioned pilot and having a collar, and a heat responsive element in position to be heated by the first mentioned pilot and 75

movable into and out of the path of the collar, said last mentioned heat responsive element being operable after the manually operable rod has been pushed and the first mentioned pilot has been lighted to move into the path of and engage the collar so that the first mentioned valve will be held in open position, and being operable when the first mentioned pilot is extinguished to move out of engagement with the collar so that the first mentioned valve may be moved by its spring to closed position.

2. The combination with a plurality of burners, a gas supply conduit therefor, a pilot for lighting certain of said burners, a valve controlling the flow of gas through the conduit to said burners, a spring tending to close said valve, a manually operable push rod for opening said valve, said rod extending over the pilot and having a collar, a heat responsive element in position to be heated by the pilot and movable into and out of the path of the collar, said heat responsive element being operable after the rod has been pushed and the pilot has been lighted to move into the path of and engage the collar so that the valve will be held in open position and being operable when the pilot is extinguished to move out of engagement with the collar so that the valve may be moved by the spring to closed position, two more pilots for lighting other of said burners, means on the supply side of the valve for conducting gas to said last mentioned two pilots, a conduit for conducting gas from one of said last mentioned two pilots to the first mentioned pilot, thermostatic valve means in said last mentioned conduit responsive to the heat of one of said last mentioned two pilots, and other thermostatic valve means within said last mentioned conduit responsive to the heat of the other of said last mentioned two pilots, the arrangement being such that the supply of gas to the first mentioned pilot will be cut off when either of the last mentioned two pilots is extinguished, thus causing the first mentioned pilot to be extinguished so that the spring for the first mentioned valve will close the same and cut off the supply of gas to the burners.

3. In combination, a burner, a pilot in lighting proximity to said burner, a second burner, a pilot in lighting proximity to said second burner, a gas supply conduit for said burners, a valve controlling the flow of gas through said conduit to said burners, a second valve, a conduit for conducting gas from the supply side of said supply conduit to the second valve, branch conduits for conducting gas from the second valve to the pilots, the branch conduit to the second pilot being upon the supply side of the second valve, the branch conduit to the first pilot being upon the discharge side of said second valve, a heat re-

sponsive element in position to be heated by the second mentioned pilot when lighted, means movable by the heat responsive element when heated by the second mentioned pilot for opening the second mentioned valve, said second mentioned valve being movable to closed position to cut off the supply of gas to the first mentioned pilot when the second mentioned pilot is extinguished, a manually operable push rod for opening the first mentioned valve, said rod having a projection, and a heat responsive element in position to be heated by the first mentioned pilot and movable into and out of the path of the projection, said last mentioned heat responsive element being operable after the manually operable rod has been pushed and the first mentioned pilot has been lighted to move into the path of and engage the projection so that the first mentioned valve will be held in open position, and being operable when the first mentioned pilot is extinguished to move out of engagement with the projection so that the first mentioned valve may be moved to closed position.

4. The combination with a plurality of burners, a gas supply conduit therefor, a pilot for lighting certain of said burners, a valve controlling the flow of gas through the conduit to said burners, a manually operable rod for opening said valve, said rod having a projection, a heat responsive element in position to be heated by the pilot and movable into and out of the path of the projection, said heat responsive element being operable after the rod has been actuated and the pilot has been lighted to move into the path of and engage the projection so that the valve will be held in open position and being operable when the pilot is extinguished to move out of engagement with the projection so that the valve may be moved to closed position, two more pilots for lighting other of said burners, means on the supply side of the valve for conducting gas to said last mentioned two pilots, a conduit for conducting gas from one of said last mentioned two pilots to the first mentioned pilot, thermostatic valve means in said last mentioned conduit responsive to the heat of one of said last mentioned two pilots, and other thermostatic valve means within said last mentioned conduit responsive to the heat of the other of said last mentioned two pilots, the arrangement being such that the supply of gas to the first mentioned pilot will be cut off when either of the last mentioned two pilots is extinguished, thus causing the first mentioned pilot to be extinguished so that the first mentioned valve will close and cut off the supply of gas to the burners.

THOMAS L. FERRALL.
